UNITED STATES PATENT OFFICE.

CHARLES SEARS, OF CLEVELAND, OHIO.

TYPE-BAR-CASTING MACHINE.

SPECIFICATION forming part of Letters Patent No. 596,340, dated December 28, 1897.

Application filed October 22, 1896. Serial No. 609,662. (No model.)

To all whom it may concern:

Be it known that I, CHARLES SEARS, a citizen of the United States, residing at Cleveland, in the county of Cuyahoga and State 5 of Ohio, have invented certain new and useful Improvements in Type-Bar-Casting Machines; and I do hereby declare the following to be a full, clear, and exact description of the invention, such as will enable others skilled 10 in the art to which it appertains to make and use the same.

The machine shown in the drawings is one which is particularly designed to form type-bars by casting upon the edge of previously- 15 prepared slugs or blanks a thin strip of type-metal having on its face printing-characters which correspond with the characters on a previously-prepared matrix. The matrices which are intended to be used with the machine are those which are formed by imprinting the characters into the end fibers of strips of wood of uniform size; but matrices of other kinds may be used, or an entire type-bar may be cast either with the particular machine 20 shown or with machines of modified construction, but nevertheless employing the invention or material parts thereof, as set forth in the claims.

The principal object of the invention as embodied in the machine shown is to automatically and rapidly form the described kind of type-bars from a stock of previously-prepared matrices. One result which has in particular been aimed at is the casting upon the 25 blank of character-carrying edges which shall have perfect printing-surfaces and no blow-holes or other imperfections.

The invention consists in the construction and combination of parts hereinafter described and claimed.

In the drawings, Figure 1 is a front elevation of so much of the machine as contains my invention. Fig. 2 is a plan view thereof when the removable part of the casting-box 45 has been removed. Fig. 3 is a sectional end view on line 3 3 of Fig. 2. Fig. 4 is a sectional view of the plane indicated by line 4 4, and Fig. 5 is a plan view of the hopper. Fig. 6 is a bottom plan view of plate G, enlarged.

50 The drawings do not show the melting-pot, pump, or the connection between the nozzle

and pump, because there is nothing new in the form of these parts which I propose to use, and such parts having any suitable construction may be used.

55

Referring to the parts by letters, A represents the bed-plate of the machine, and B the hopper, secured thereon, having two compartments $b' b^2$, separated by a partition b , in which are respectively placed a stock of matrices I 60 and type-bar blanks J. A feed-slide C, having two arms $c' c^2$, is movable between guides $a a$ on the bed-plate and is periodically advanced to carry the bottom matrix and blank from the hopper into the casting-box. The 65 slots $b^3 b^4$ are formed in the bottom of the sides of the hopper to permit the described movement of the slide and the matrix and type-bar. The arm c normally projects through the slot b^3 into the compartment b' , 70 which contains the blanks, and the column of blanks rests upon this slide-arm. On this arm, just to the right of the blanks, is a shoulder c^2 , which is not quite as high as the blanks are thick. The end of the slide-arm c' lies 75 normally just to the right of the lowest matrix. When the slide is moved to the left, the shoulder c^2 and the end of the arm c' respectively engage with the lowest blank and matrix and push them through the slots b^4 80 into the casting-box. The slide may be moved by any suitable mechanism, but I have shown a gear-segment F, which engages with a rack c^3 on the slide, which segment is oscillated by means of a rocker-arm H, which is connected 85 with the gear-segment by a pitman f. The said arm H is rocked by a crank-pin k on a driven shaft K, which pin works in a slot h in the arm H. Any other mechanism for periodically operating the slide C might be employed. The two arms of the slide are constructed differently, as described, because the blanks are not so thick as the matrices with which the machine is especially organized to work.

95

The casting-box, which is placed upon the bed-plate, is movable a short distance toward and from a nozzle L, placed between itself and the hopper for the purpose of periodically making the necessary connection with said 100 nozzle. This nozzle extends vertically up through the bed-plate. Its end is turned over

into horizontal position and is directed toward the casting-box. The end of this nozzle is tapered slightly.

The bottom plate D of the casting-box rests 5 upon the bed-plate between the two longitudinal guides $a^2 a^2$. Near the middle of this plate and in line with the partition in the hopper is a raised longitudinal rib d, extending from one end to the other. A laterally-movable bar E, parallel with the rib d, lies upon the plate D beneath the flange d^2 . Two levers e e are pivoted at their lower ends to the plate D and their upper ends are connected together by a bar e'. These levers are connected 15 by links e^2 with the bar E.

Two pins $d^3 d^3$, mounted in one of the guide-blocks a^2 , pass through horizontal slots in a vertical flange d^4 on the rear edge of the plate D. Their outer ends are connected together 20 by a bar d^5 .

M represents a housing for the vertically-movable members of the casting-box, and this housing is fastened to the bed-plate by a screw or screws which pass through the foot m of 25 the housing. This housing is provided with a handle m', by which this housing and all that it supports may be lifted off when these screws are removed. The horizontal grip or handpiece m² is made of glass, wood, or some 30 other non-heat-conducting material.

N represents a shaft which is journaled in the sides of the housing, and to it are secured three cams n n' n', the two outer cams n' being alike. This shaft is revolved constantly, 35 being connected by gears with the main driving-shaft P.

G represents the top mold-plate, which has a bifurcated stem g, in the forks of which the transverse vertical slots g' are formed.

40 R R represent two vertically-movable gates, the lower ends of which are movable in vertical slots through the plate G. In both of these gates are the transverse vertical slots r, near their upper ends. The shaft N extends through the slots r and g' in said gates R R and the stem g, and the cams n' n' and n engage with the said gates and stem, respectively, to move them up or down, as the case may be.

45 In the bottom of the plate g are two spring-actuated presser-feet g² g³, whose ends adjacent to the hopper are beveled, whereby the matrices and blanks may slide beneath them, the functions of these presser-feet being to 50 press the blank and the matrix down upon the bottom plate D and prevent them from moving too far. A vertical pin d', which is set in the bottom plate D, passes into a hole in the top mold-plate G, which permits said 55 mold-plate to move independently in a vertical direction, but which compels both plates to move together horizontally.

The bottom blank J and the bottom matrix I are respectively moved out of the hopper 60 and into the mold-box by the two arms of the slide C. The blank, as before stated, rests upon the arm c. The blank in passing into

the casting-box engages with the lower end of a beveled spring-pin g⁴, which is seated in the top plate G, thereby lifting the pin, which, 70 after the blank has passed it, flies down behind the blank. Therefore when the slide is retracted the blank must remain in the casting-box upon the plate D. The matrix and the blank are now in the casting-box, resting 75 upon the plate D, respectively in front of and behind the rib d. The lever Q, which is pivoted to the housing M, has a slot q in its lower end which engages with the bar e'. Its upper end is engaged by a cam s' on a shaft S, which 80 is mounted in the housing. The rocking of this lever causes the bar E to move laterally and push the matrix-block I against the front face of the rib d, and also against a shoulder g⁷ on the lower face of the plate G, which 85 shoulder is in the same vertical plane as the front face of said rib d. At the same time the blank J is moved by the pins d³ toward the matrix-block and into contact with the rear face of the same rib d. The space between 90 the rib d and plate G and between the matrix and the blank type-bar is the mold-space to be filled with metal to finish the type-bar. The pins d³ are moved by means of a bell-crank lever T, pivoted to an upright post u². The 95 lower arm of this lever is slotted and embraces the bar d⁵. The other arm of the lever is engaged by a cam u on a shaft U, which is mounted in fixed posts u', and a contractile 100 coil-spring t is secured to the other arm of the lever and to a fixed arm v². The action of the cam upon the lever moves the pins d³ inward to force the blank toward the matrix, as described. The spring t causes the withdrawal 105 of said pins. As the matrix and blank are moved in the casting-box they slide beneath the two presser-feet g² g³, which prevent them from acquiring a momentum which will carry them beyond the point to which they are positively pushed. The top plate G is moved 110 down so that it bears upon the top of the blank by the action of the cam n. The gates R R are also moved down by the cams n' n'. The distance between the proximate faces of 115 these gates is exactly equal to the length of the blank J. Wherefore said gates bear against the ends of the blank. The gates R have forwardly projecting vertical knife-edges r', which cut into the face of the matrix-block. When the parts have reached the position described, the space between the matrix and the blank is entirely closed, except for a hole r² through the right-hand gate R, which hole is directly in line with the nozzle L. The entire 120 casting-box is then moved to the right. Said 125 hole embraces the nozzle, being tightly closed thereby, and when the parts are in this position molten metal is injected through the nozzle into the inclosed mold-space from the end thereof. I have discovered after much 130 experimenting that when the molten metal is injected from the end of the mold-space the strip of metal bearing the printing-characters is substantially without blow-holes and the

printing-surface is practically perfect. The results in these particulars are much better than when the molten metal is injected from the side or top or bottom of the mold-space. 5 This endwise movement of the casting-box is effected by means of a lever *W*, which is pivoted to a stud *w*, which is secured to the rear side of the housing. The lower end of this lever is slotted and it embraces a rearwardly-projecting pin *g*⁵, secured to the plate *G*. The upper end of this lever is beveled and is adapted to be struck by the two beveled arms *p p'*, which are secured to the driving-shaft *P*. One of these arms strikes one side of the lever and rocks it in one direction, which causes the casting-box to be moved to the right into the described engagement with the nozzle. The other arm strikes this lever, rocks it in the contrary direction, and causes 15 the casting-box to be moved in the reverse direction. The continued revolution of the driving-shaft causes all the parts of the casting-box to reverse their motion after the printing edge has been cast upon the blank. 20 Another advance of the slide *C* pushes another matrix and another blank into the casting-box, and they push before them, out of the casting-box, the matrix which has just been used and the completed type-bar which has 25 just been formed. These results proceed automatically and indefinitely so long as the machine is run and matrices and blanks are supplied to the hopper.

Having described my invention, I claim—

35 1. In a type-bar-casting machine, the combination of a casting-box adapted to hold a matrix having a plurality of aligned characters and to inclose a type-bar-mold space in line with the character-line upon said matrix, 40 with means for delivering molten metal into the mold-space from one end thereof, that is to say, from a point at one side of the characters, whereby the molten metal will flow into said space in a direction transverse to the said characters, substantially as and for the purpose specified.

45 2. In a type-bar-casting machine, the combination of a casting-box containing a recess for a type-bar blank, and mechanism for holding a matrix in parallel relation to said type-bar blank, and mechanism for inclosing the space between them, with a nozzle adapted to direct molten metal into said space from one end thereof, substantially as and for the purpose specified.

55 3. In a type-bar-casting machine, the combination of a casting-box adapted to receive a prepared matrix and a type-bar blank, and to hold them in parallel relation at the proper distance apart, and means for inclosing the space between them, with a nozzle, and mechanism for introducing the nozzle into the end of said inclosed space, substantially as and for the purpose specified.

60 4. In a type-bar-casting machine, the combination of a longitudinally-movable casting-

box adapted to hold a prepared matrix and a type-bar blank in parallel relation and at the proper distance apart, and mechanism for inclosing the space between them except for a 70 hole at one end of said space, with a fixed nozzle adapted to enter and close said hole, and mechanism for moving the casting-box toward and from the nozzle, substantially as and for the purpose specified. 75

5. In a type-bar-casting machine, the combination of a casting-box consisting of a bottom mold-plate adapted to support a matrix and a type-bar blank, and having a raised rib between them, mechanism for forcing said 80 matrix and blank against said rib, a vertically-movable top mold-plate, and two vertically-movable end gates, whereby the matrix and blank are held in parallel relations and the space between them is inclosed, with a 85 nozzle for directing molten metal into said inclosed space, substantially as and for the purpose specified.

6. In a type-bar-casting machine, in combination, a hopper adapted to contain a supply of prepared matrix-blocks and type-bar blanks, a casting-box movable toward and from said hopper, a slide for pushing the matrix-blocks and blanks from the hopper and into the casting-box, mechanism for holding 95 said matrix-blocks and blanks in the casting-box in parallel relations and at the proper distance apart, and for inclosing the space between them except for a small hole at one end of said space, with a fixed nozzle located 100 between the casting-box and hopper, and mechanism for moving the casting-box toward and from said nozzle, substantially as and for the purpose specified.

7. In a type-bar-casting machine, in combination, a longitudinally-movable bottom mold-plate having a longitudinal raised rib, a hopper adapted to contain a stock of prepared matrices and type-bar blanks, mechanism for moving a matrix-block and a blank 110 from the hopper onto said plate on opposite sides of said rib, mechanism for forcing said matrix-block and blank against said rib, a top mold-plate movable vertically independently of the bottom plate, connections between 115 said plates whereby they must move longitudinally together, end gates vertically movable in guides in the top plate, one of said gates having a hole in which the nozzle will fit, a fixed nozzle, and mechanism for moving a 120 casting-box toward and from the nozzle, substantially as and for the purpose specified.

8. In a type-bar-casting machine, in combination, a bottom mold-plate having a longitudinal raised rib, a vertically-movable top mold-plate having two spring-actuated presser-feet in its lower side, mechanism for moving a matrix-block and a type-bar blank onto the bottom plate on opposite sides of said rib and beneath said presser-feet, mechanism for moving the matrix-block and blank against said rib, end gates for closing the ends 130

of the space between said matrix-block and blank, and a nozzle for directing molten metal into the inclosed space between said matrix-block and blank, substantially as and for the 5 purpose specified.

9. In a type-bar-casting machine, in combination, a casting-box consisting of a longitudinally-movable bottom mold-plate adapted to support a matrix-block and type-bar 10 blank, and having a raised longitudinal rib between them, a housing, a top mold-plate which is movable vertically and horizontally in said housing, a vertical pin d' , two end gates, one having a hole, a cam-shaft mounted 15 in the housing, cams thereon for operating said top mold-plate and gates, a fixed nozzle, and mechanism for moving the casting-box toward and from the nozzle, substantially as and for the purpose specified.
10. In a type-bar-casting machine, in combination, a horizontally-movable casting-box adapted to hold a matrix-block and a type-bar blank in parallel relations and at the 20 proper distance apart, means for inclosing 25 the space between them except for a hole at one end thereof, a fixed nozzle having a horizontal tapered end, and mechanism for moving said casting-box toward and from the nozzle to cause it to enter and withdraw from 30 said hole, substantially as and for the purpose specified.

11. In a type-bar-casting machine, the combination of a longitudinally-movable bottom plate D, having a rib d , the housing M, cam-shaft N, and cams n n' n'' , top mold-plate G having a stem which is slotted and embraces the shaft N, two gates R R which slide through 35 the bottom plate and are slotted and embrace the said shaft, one of said gates having a nozzle-hole, the pin d' , the fixed nozzle L, and mechanism for moving the two plates and 40

gates, substantially as and for the purpose specified.

12. In a type-bar-casting machine, the combination of a longitudinally-movable bottom 45 plate D having a raised rib d , and a removable housing M, with a vertically-movable top plate G, end gates R, and their operating mechanism supported by said housing, substantially as and for the purpose specified. 50

13. In a type-bar-casting machine, the combination of a bottom mold-plate having a raised rib, means for introducing a matrix-block and a blank onto said plate on opposite sides of said rib, mechanism for pushing 55 said matrix and blank laterally into contact with said rib, with a vertically-movable top mold-plate, the spring-actuated presser-feet carried thereby, the vertically-movable end gates having vertical knives on the edges 60 which face the matrix-block, and means for directing molten metal into the inclosed space between the matrix-block and blank, substantially as and for the purpose specified.

14. In a type-bar-casting machine, the combination of a hopper having two compartments, both sides of which are slotted at the bottom, a slide having two arms, one of which extends across one of the compartments and has a shoulder c^2 , with a casting-box consisting of a bottom plate, a vertically-movable top plate, and end gates, and a beveled spring-pin g^4 , which projects down from said top plate, substantially as and for the purpose specified. 70 75

In testimony whereof I affix my signature in presence of two witnesses.
